US00D829740S

(12) **United States Design Patent** (10) Patent No.: **US D829,740 S**
(45) Date of Patent: ** Oct. 2, 2018

(54) **COMPUTER DISPLAY WITH MENU SCREEN**

(71) Applicant: **DEKA Products Limited Partnership**, Manchester, NH (US)

(72) Inventors: **Allison E. Lepine**, Concord, NH (US); **Constance D. Pitenis**, Hooksett, NH (US); **Erik N. Sabin**, Manchester, NH (US)

(73) Assignee: **DEKA Products Limited Partnership**, Manchester, NH (US)

(**) Term: **15 Years**

(21) Appl. No.: **29/579,662**

(22) Filed: **Sep. 30, 2016**

(51) LOC (11) Cl. **14-04**

(52) U.S. Cl.

USPC **D14/486**

(58) **Field of Classification Search**

USPC D14/485, 486, 487-488, 489-495
CPC G06F 3/0481; G06F 3/048; G06F 3/04842;

G06F 3/04845; G11B 19/025
